US00D867035S

(12) **United States Design Patent** (10) **Patent No.:** **US D867,035 S**
Brugger et al. (45) **Date of Patent:** **** Nov. 19, 2019**

(54) **RETAIL FIXTURE**(71) Applicant: **Apple Inc.**, Cupertino, CA (US)

(72) Inventors: **Alice Marlin Brugger**, San Francisco, CA (US); **Manuel DeJesus**, San Francisco, CA (US); **Joshua Robert Edwards**, Santa Cruz, CA (US); **Jean-Marc Gady**, Los Altos, CA (US); **Wesley Bryan Hamm**, San Francisco, CA (US); **Russell John Kaaihue Heirakuji**, Cupertino, CA (US); **Allison Inouye**, San Francisco, CA (US); **Moritz Wilsberg**, Menlo Park, CA (US)

(73) Assignee: **Apple Inc.**, Cupertino, CA (US)(**) Term: **15 Years**(21) Appl. No.: **29/656,127**(22) Filed: **Jul. 10, 2018**(51) LOC (12) Cl. **06-06**

(52) U.S. Cl.

(57) **CLAIM**

The ornamental design for a retail fixture, as shown and described.

DESCRIPTION

FIG. 1 is a top front perspective view of a retail fixture showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the retail fixture that form no part of the claimed design.

1 Claim, 5 Drawing Sheets
